SOUND RECORD REPRODUCING DEVICE

Josef Holy, Vienna, Austria

Application June 16, 1933, Serial No. 676,074
In Austria May 5, 1933

1 Claim. (Cl. 274—16)

The sound boxes hitherto employed in sound record reproducing devices are not cheap and difficult and relatively expensive to repair. Moreover, secondary noises are often produced by the sound boxes, so that the purity of the reproduced sound is considerably impaired.

This invention has for its object to replace the sound box by a simple and much cheaper arrangement which renders possible a direct reproduction of the sound record with purity of sound. The novelty consists chiefly in the fact that a metal tongue carrying a gramophone needle is connected to a carrier which does not transmit natural oscillations and which is adapted to be fitted in to the tone arm, a diaphragm being carried on the tongue by means of a rod projecting therefrom at an angle.

An embodiment of the invention is illustrated by way of example in the accompanying drawing in which:—

Fig. 1 shows the device in side elevation partly in section mounted on the tone arm of a gramophone.

Fig. 2 is an end view of Fig. 1, the diaphragm being removed.

An arm shaped carrier 1 has a lateral projecting pin 2 adapted to be inserted in the sleeve shaped end of the tone arm 11 of a gramophone. The carrier 1 together with the pin 2 is relatively heavy or so constructed that it does not transmit oscillations during the sound reproduction. The carrier 1 carries on the side remote from the pin 2 a flat metal tongue 3 which is fixed only at its upper end to the carrier 1 by a screw 4. The metal tongue 3, which need not rest along its entire length on the carrier 1, carries on its other end a holder 5 of known type for fixing a

gramophone needle 6. The tongue 3 carries behind the holder 5 a metal rod 7 projecting at right angles or at some other suitable angle on the free end of which a diaphragm 8 is detachably secured. The diaphragm 8 in the example illustrated forms a flat funnel which is mounted on the free end of the rod 7 by means of a sleeve 9 extending from the apex of the funnel and fixed by a clamping screw 10. In this way the tongue 3 is separated from the carrier 1 throughout its length except where the parts are fixed together by the screw 4.

When reproducing sound, the rod 7 and the diaphragm 8 are oscillated by the needle 6 running in the groove of the record in the usual manner, an extremely pure sound reproduction free from secondary noises being obtained. By suitably selecting the length of the rod 7 and the size or conical shape of the diaphragm 8 the timbre of the sound reproduction can be determined as desired.

I claim:—

Sound record reproducing device for gramophones, comprising in combination with the tone arm having a sleeve shaped end, a carrier insensitive for the taking up of oscillations inserted in the sleeve-shaped end of said tone arm, a metal tongue bearing against and fixed only at its upper end to said carrier, a needle mounted at the lower end of said tongue and adapted to transmit oscillations to said tongue, a metal rod fixed at one end to said tongue near the lower end thereof and adapted to transmit the movements of said tongue, and a diaphragm mounted on the other end of said rod adapted to be actuated by said rod.
